9214

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,101, dated June 24, 1884.

Application filed May 12, 1884. Term of patent 3½ years.

To all whom it may concern.

Be it known that I, SARAH JANE SHIELS, of the city, county, and State of New York, have invented and produced a new and original Design for a Pattern of a Lady's Costume, (numbered 9,214;) and I do hereby declare that the engraved prints accompanying this specification convey to any one accustomed to using paper patterns a clear understanding of how a garment made up by the pattern will appear.

The design shows a round walking-skirt and a basque. The skirt displays a lower front drapery falling in a deep point at the right side and exhibiting a gathering in its left side edge; an upper front drapery, falling in a point at the right side, and displaying gatherings in each side edge; and a full back-drapery,

falling in two deep points nearly to the bottom of the skirt, and exhibiting gatherings in its front edges and loopings at the center. The basque displays closely-fitted fronts that describe a point below the closing, and a broad deep tabat each side; a closely-fitted back, falling in three deep tabs below the waist-line; a standing collar, and coat sleeves that exhibit gathers and a high roll at the shoulders.

What I claim as my invention, and desire to secure by Letters Patent, is:

The design for a lady's costume, as shown in the engraved prints accompanying this specification.

SARAH JANE SHIELS.

Witnesses:

MARCELLUS CARLETON SHATTUCK,
ALFRED FRANCIS.
